UNITED STATES PATENT OFFICE.

BACON S. TRICE, OF CORPUS CHRISTI, TEXAS.

COMBINED HAT AND COAT RACK.

1,116,765.

Specification of Letters Patent.

Patented Nov. 10, 1914.

Application filed February 10, 1914. Serial No. 817,884.

To all whom it may concern:

Be it known that I, BACON S. TRICE, a citizen of the United States, residing at Corpus Christi, in the county of Nueces and State of Texas, have invented certain new and useful Improvements in Combined Hat and Coat Racks, of which the following is a specification.

It is the object of the present invention to provide a combined hat and coat rack of simple construction, wherein a hat holder is supported by two garment hooks in such a way as to form a compact structure, easily mounted on a wall or other support.

With this and other objects in view, the invention consists of the construction and arrangement of parts illustrated in the accompanying drawings, in which—

Figure 1 is a perspective view of the rack, and Fig. 2 is a plan view of a modification.

Referring specifically to the drawing, each of the garment hooks 5 is formed from a strip of metal, bent intermediate its ends to form two vertically spaced arms 6 and 7, respectively. The arms are curved upwardly and their inner ends are bent in opposite direction, substantially at right angles to the arms, as indicated at 8 and 9. The bent portions are provided with holes and are secured to a wall or other support by screws or other fastening means 10.

Two hooks are provided, and a hat holder is located between the hooks and supported by them. The hat holder, which is preferably made of heavy wire, is curved at its middle portion to form a loop 11 adapted to hold the crown of a hat. The extremities of the hat holder extend horizontally in opposite directions, as indicated at 12, a distance sufficient to accommodate the rim of a hat, and then downwardly as shown at 13. The arms 6 and 7 of the hooks are provided with a pair of vertically aligned

perforations 14, through which the vertical portions 13 of the hat holder extend. The arms 6 and 7 of the hooks are vertically spaced from each other, which makes the hooks stronger and enables them to hold the portions 13 of the hat holder more securely in a vertical position.

A hat is placed in the holder so that the crown rests in the loop 11, and the rim lies flat against the wall, between the wall and the holder. Thus the hat is held securely and cannot accidentally fall down.

A modification is shown in Fig. 2 wherein a number of hooks 5 are secured to a wall, and each pair of hooks carries a hat holder between them. The intermediate hooks are provided with two pairs of perforations 14 in order to accommodate the adjacent ends of two hat holders.

I claim:

1. A combined hat and coat rack comprising hook members provided with vertical apertures, and a U-shaped holder having outwardly and downwardly extending extremities, the downwardly extending portions passing through the apertures in the hook members.

2. In a combined hat and coat holder, hook members having vertically spaced arms connected at their outer ends, said arms having vertically aligned apertures, and a hat holder located between the hooks, the hat holder comprising a downwardly extending U-shaped member having outwardly and downwardly extending extremities, the downwardly extending portions passing through the apertures in the hook members.

In testimony whereof I affix my signature in presence of two witnesses.

BACON S. TRICE.
